CAP FEED FOR DOUBLE SEAMING MACHINES

Henry L. Guenther, Los Angeles, Calif.

Application August 4, 1928. Serial No. 297,569

12 Claims. (Cl. 113—14)

This invention relates to can making machinery and particularly pertains to a cap feeding mechanism for a double seaming machine.

It is the principal object of the present invention to provide a cap feeding mechanism for use in connection with a can double seaming machine, and which mechanism will operate automatically as initially actuated by a can to feed a cap to said can incident to a first double seaming operation. Said mechanism being especially suitable for use in connection with the double seam spindles and head of the machine shown in my application entitled Double seaming machine filed concurrently herewith, in which cans are consecutively delivered to the cooperating chucks and spindles of a seaming station and after which the can is lifted to abut against the underface of a cap chuck by the mechanism with which the present invention is concerned and by which the can and cap are then seamed together; said mechanism embodying the use of a novel "no can no cap" feed and means for rounding the mouth of the can and insuring that it will be properly assembled with the associated cap.

The present invention contemplates the provision of a run along which cans are positively fed, and adjacent to which a "no cap no can" trip lever is supported to be encountered by the traveling can feed lever acting to render a cap feed device operative and to insure that a cap will be cut from a stack, fed through a marker and delivered to the can at the double seaming station.

The invention is illustrated by way of example in the accompanying drawings in which:

Fig. 1 is a fragmentary view in plan showing the mechanism with which the present invention is concerned.

Fig. 2 is a fragmentary view in side elevation showing the cap feed mechanism, the marker and the means for rounding the can.

Fig. 3 is a fragmentary view in vertical section as seen on the line 3—3 of Fig. 1, and showing the cap feed interlocking mechanism.

Fig. 4 is a view in perspective drawn on an enlarged scale and showing the operating pawl of the interlocking mechanism.

Fig. 5 is a view in perspective drawn on an enlarged scale showing the lock bar of the interlocking mechanism.

Fig. 6 is a view in plan showing a fragmentary portion of a double seaming machine with the cap feed associated therewith and with parts broken away to more clearly show the initial, intermediate and final positions of a cap, and

disclosing the operating mechanism in its intermediate position.

Fig. 7 is a fragmentary view in plan similar to that shown in Fig. 6, disclosing the cap feed mechanism in its final position.

Fig. 8 is a fragmentary view in side elevation showing the interlocking mechanism of the cap feed.

Fig. 9 is a fragmentary view in vertical section as seen on the line 9—9 of Fig. 6, and showing the parts disclosed in Fig. 3 with the exception that it shows the operating pawl in its released position.

Fig. 10 is a fragmentary view in transverse vertical section as seen on the line 10—10 of Fig. 6, and as showing a can run in the manner in which a can is positively fed therealong.

Fig. 11 is a view in vertical section through the cap feed mechanism as seen on the line 11—11 of Fig. 6, and disclosing the cap feed mechanism with a cap in the marking position.

Fig. 12 is a view in vertical section through the cap feed mechanism taken longitudinally of its path of travel and showing it at the extreme initial end of its stroke.

Fig. 13 is a fragmentary view in longitudinal section through the cap feed mechanism particularly showing the manner in which a cap is fed to a position over a can and the manner in which a can is lifted to project into the cap.

Fig. 14 is a view in transverse vertical section through the cap feed mechanism as seen on the line 14—14 of Fig. 13 and particularly showing the cap guides and the manner for preventing retraction of a cap which has reached the marking station.

Fig. 15 is a view in vertical section through the cap feed mechanism as seen on the line 15—15 of Fig. 14, and particularly shows the cap catch at the marking station.

Fig. 16 is a transverse sectional view on line 16—16 of Fig. 7.

Fig. 17 is a longitudinal sectional view on line 17—17 of Fig. 16, showing the relation between the separating knife and the cap discharge slot.

Fig. 18 is a fragmental detail of the pitman connection to the driving head.

Fig. 19 is a view in transverse section through the marking device as seen on the line 19—19 of Fig. 11.

Referring more particularly to the drawings, 10 indicates the floor of a runway along which cans 11 are fed. This runway is defined by spaced side rails 12 and 13 which guide the can as it is advanced by an endless conveyor 14.

110

This conveyor carries a plurality of driving flights 15 which move into a position in the rear of a can and positively engage and advance the can along the runway. The ends of the guide rails 12 and 13 terminate in curved portions 17 and 16, respectively. These portions act to divert a can from its straight path of travel and into one of a series of pockets 18, carried on a star wheel 19. The star wheel 19 is a part of a 5 double seaming machine generally indicated at 20. In the present instance an initial seaming station 21 occurs at the point at which the can is ejected from between the curved ends 16 and 17 of the guide rails of the runway. This 10 double seaming station is defined by a lower chuck plate 22 carried on a vertically moving spindle 23 and an upper chuck plate 24 carried on a vertically fixed spindle 25 and between which the can 11 and an associated cap 26 may 15 be clamped in an assembled position. The exact mechanism for accomplishing this result is more specifically disclosed in my copending application Double seaming machine, filed concurrently herewith.

20 Disposed on a longitudinal center line at right angles to the path of the cans as defined by the guide rails 12 and 13 and intersecting the rotary axis of the star wheel 19 is an automatically acting cap feed mechanism 27. This mechanism 25 comprises a plurality of columns 28 forming a cap stacker, generally indicated at 29, and between which a stack of the caps 26 may be positioned to feed downwardly by gravity. A ring 30 receives the lower ends of the columns 28, and is formed with a central opening through which the caps may pass as they are cut from the bottom of the stack of caps in the manner which will be hereinafter set forth. The ring 30 is mounted in spaced relation to and above a cap feed bed plate 31 by means of bolts 32 and spacing bosses 33. This space is provided to accommodate a cap feed frame 34 which reciprocates horizontally beneath the cap stack. This frame 38 comprises a cross-head 35, carrying 35 a pair of parallel feed blades 36 and 37, respectively. These blades extend forwardly and in their extreme forward position their outer ends assume positions at diametrically opposite sides of the axis of the can onto which a can cap is 40 to be fed. In order to permit the cap to be lifted free of these forward ends when in the extreme forward position, the opposing faces of the blades are cut away in arcuate form to provide clearances for the lifted cap, as clearly 45 shown at 38 and 39 of Figs. 1, 6 and 7 of the drawings. The feed blades as shown particularly in Fig. 13 of the drawings, are formed with longitudinally extending grooves 40 along which one of the caps 26 may move. In Fig. 17 these 50 grooves are shown in communication with the throat of a feed slot 41 indicated in dotted lines in Fig. 13, and which slots are on the opposing faces of the blades. These slots are so arranged as to form a horizontally and rearwardly extending point 42 adapted to slip between the lowermost cap 26 of the stack and the superjacent cap, and to cut this cap from the stack as the blades move in the direction of the arrow "a" 55 as indicated in Fig. 13. This will separate the lowermost cap from the stack and move it to a lower plane than the bottom of the stack and in the horizontal plane of the grooves 40. The feed blades move in unison with a pusher finger 43 which engages the rear edge of the cap cut 60 from the stack and shoves it forwardly along the 55

grooves 40 of the blade extensions. This forward movement is limited by the forward movement of the cross-head 35, which is driven in a manner to be hereinafter explained.

The distance which the cap is moved from beneath the stack and toward the first seaming station is calculated to cause the finger 43 to discontinue its advance of the cap when the cap has moved to a stamping position beneath the stamping die 44 which is interposed substantially midway the length of the path of travel from the cap stack to the first seaming station.

The die 44 may be operated in any desired manner, but is here shown as operated by a rocker arm 45 carried on suitable brackets 46 and connected to an operating cam 47 on a driving shaft 48 by a pitman rod 47'. The die 44 comprises upper and lower members carried by a fixed jaw 44' and a movable jaw 46', which jaws are pivoted to each other at 48'. The movable jaw is operatively connected to the rocker arm 45 by a shackle link 45'. As the cap is moved forwardly by the finger 43 it passes beneath a lock ball 49, as clearly shown in Fig. 15 of the drawings. This ball thus prevents retraction of the cap 26 when 100 the feed blades are retracted, since the ball is yieldably held in the path of travel of the cap by a spring 50. The ball and its spring are carried in an adjustable cage 51 secured by a screw 52 in an adjustable position with relation to a 105 bracket 53 formed with a longitudinally extending slotted opening 54.

A cap feed pawl 55 is oscillatably mounted, between the cutaway ends 38 and 39 of the feed blades 36 and 37, in the cap feed frame 34 by 110 means of a pivot 56. This pawl swings vertically, and is positioned in alignment with the longitudinal center of the pusher finger 43, and is intended to supplement the action of this finger in completing the delivery of a cap from the 115 stack to the first seaming station. A spring 57 is disposed under the forward end of the pawl 55 and yieldably holds its point 58 in its uppermost position while permitting it to be depressed as the feed carriage is retracted and the pawl is 120 moved beneath a cap temporarily held by the lock ball 49 at the marking station. Forward movement of the feed carriage will cause the point 58 of the pawl 55 to engage the rear edge of a cap at the marking station and to move it 125 forwardly into a counterbored recess 59 of a cap supporting ring 60. This ring has a central center opening 61 therethrough, the wall of which opening tapers downwardly and outwardly as indicated at 62. The axis of the opening 61 130 is in longitudinal alignment with the chucks 22 and 24 of the first seaming station and when a can is moved to the first seaming station it will be disposed beneath said openings and centrally aligned therewith.

The star wheel 19 as previously described, is formed with a plurality of pockets 18 adapted to receive the cans. These pockets engage the cans in a plane lower than the lip of the can and are struck on an arc which will conform to the contour of a can of a particular diameter being passed through the machine and will embrace substantially one half of the circumference thereof. When the can is at the seaming station it is embraced upon the opposite side of the recess by 145 a semicircular mold member 63. This member is carried by the feed blade structure of the cap feed mechanism, and is secured thereto by a bracket 64 and cap screws 65, for a purpose which will be hereinafter set forth.

The cap feed structure carriage which includes the crosshead 35 and feed blades 36 and 37, normally stands in an inoperative position disconnected from any actuating mechanism. This is controlled by the movement of the "no can no cap" trip lever 66, which has a forwardly projecting end extending into the path of travel of a can being fed along the runway and between the guide rails 12 and 13. The lever 66 extends horizontally and is carried upon a pivot 67 mounted in the floor of the can runway and at the side thereof. An extension 68 of this lever engages pitman rod 69 which is pivotally secured to a lever arm 70. The lever arm 70 is fixed to the outer end of a horizontally extending pin 71 which extends through the bed plate of the cap feed mechanism and is rotatably mounted therein. Secured upon the inner end of the pin 71 and extending through a slotted opening 72 in the bed plate is an operating pawl 73. This pawl, as more clearly shown in Fig. 4 of the drawings, has a pointed bladelike end 74 adapted to facilitate its entry into an opening 75 in a lock bar 76. This bar is slidably mounted between the guides 77 and 78 carried by and forming a part of the cap feed carriage, and by which the lock bar 76 may be guided in a movement lateral to the path of travel of the carriage.

By reference to Fig. 6 of the drawings it will be seen that the carriage is in its forward position with the feed blades disposed in relation to the cap stack, as more clearly shown in Fig. 13 of the drawings, and it is to be understood that it is in this position that the cap feed carriage normally stands at rest until actuation of the "no can no cap" lever 66 by the presence of a can in the runway. Motive power is provided for the cap feed carriage by a driving head 79 which reciprocates in a horizontal plane at the rear of the cap feed carriage and is provided with a lock notch 80 in its side with which the lock bar 76 may register when released so that upon retraction of the driving head 79 the cap feed carriage will move in unison therewith and will then be moved forwardly on the reverse stroke of the driving head.

The driving head is provided with an extension 81 projecting through a slotted opening 82 in the floor of the bed plate, and which is actuated through suitable pitman and wrist pin connections 83 pivotally secured to the outer end of an oscillating arm 84. This arm moves horizontally, and is carried upon a pivot 85. A cam arm 86 is secured to the pivot pin 85 and is provided with a pin roller 87 projecting into a cam slot 88 formed around the circumference of a barrel cam 89. This cam is mounted upon the drive shaft 48 and insures that the cap feed mechanism and the marking mechanism will move in synchronism. A sprocket wheel 90 is also carried on the driving shaft 48 and is fitted with a sprocket chain 91 extending to a sprocket on a jack shaft 92. This shaft carries a sprocket 93 around which the can feed chain 94 is placed. By this arrangement the can feed and cap feed mechanism operate in synchronism.

In operation of the present invention, cans are delivered to the runway 10 by a suitable feed and timing means, and are placed in a position where they will be successively engaged by flights 15 carried on the sprocket chain 94. This will cause a can to be positively advanced along the can runway and guided between the side rails 12 and 13. As it advances it will encounter the arcuate face of the "no can no cap" lever 66 which

is normally disposed in the path of travel of the can and at one side thereof. As the can advances it will wedge against the arcuate face of the lever 66 and cause it to swing in the direction of the arrow "b" as indicated in Fig. 1. A swinging action will take place around the vertical pivot 67 and will move the pitman rod 69 in the direction of the arrow "c" as indicated in Fig. 1, and against the tension of a spring 95. A pull on the pitman rod 69 will cause the lever 70 to swing and rotate the shaft 71 so as to move the operating pawl 73 from its locking position as shown in Fig. 3, to its releasing position as shown in Fig. 9. When it swings downwardly to its releasing position, as shown in Fig. 9, it will move beneath the lock bar 76 and out of the slotted recess 75 in the lower face thereof. This will permit the lock bar 76 to move laterally to the cap feeding means under the influence of a tension spring 96 and into the path of travel of the driving head 79 which constantly reciprocates above the floor of the cap feed table. The driving head upon its next forward stroke, at which time it is moving in the direction of the arrow "d" as indicated in Fig. 1, will engage the end of the lock bar 76 on the taper face 97 of the driving head and temporarily force it rearwardly so that the bar may then fall into the lock recess 80 of the driving head with which it will then register.

This action will cause the driving head 79 to be locked to the cap feed carriage and will act to move the cross-head 35 and the feed blades 36 and 37 with it, and initially move in a reverse direction to that indicated by the arrow "d" in Fig. 1. The result will be that the points 42 of the feed blades will enter between the lowermost cap and the superjacent cap and will cut the lowermost cap from the stack while forcing it downwardly along the inclined throats 41 of the blades and into grooves 40 at the opposite sides of the cap feed. The extreme back stroke is clearly shown in Figs. 7 and 12 of the drawings, and it will be understood that at this time a cap has been cut from the stack and is in position to be advanced as the feed mechanism moves forwardly, as indicated in Figs. 6 and 11 of the drawings. This advance action is brought about by the pusher finger 43 which moves the cap to a position beneath the marking die 44 and in advance of the lock ball 49, as shown in Fig. 15 of the drawings. In the event that another can is fed along the runway 10 and the operating pawl 73 is thus maintained in its inoperative position, it will be evident that the driving head 79 and the cap feed carriage will remain interlocked so that upon the next rear stroke of the carriage another cap will be cut from the bottom of the stack and will be advanced to the marker. Simultaneous with this action, however, it is necessary to move the cap which has just been marked, from the marking station to the double seaming station. This is brought about by the feed pawl 55 which is carried in the forward end of the carriage and upon the rear stroke thereof passes beneath the cap which is held against retraction by the lock ball 49. After passing beneath this cap the pawl then swings upwardly due to the expansive action of the spring 57 and its point 58 engages the rear edge of the cap which has been previously deposited at the marking station and will then advance this cap onto the supporting ring 60 where it will assume a position at rest in the counterbored recess 59 of this ring. Simultaneously with this advance movement of the cap, cap feed carriage will

80

150

advance the mold member 63. This member will cooperate with the recess 18 at the star wheel 19 to embrace and compress the can then present at the seaming station and will hold this can in a 5 properly rounded condition even though it has been previously distorted. While the can is thus held, the lower chuck 22 lifts the can and forces the otherwise distorted lip of the can upwardly through the opening in the cap supporting ring 10 60 as is defined by the outwardly flaring face 62 thereof. This will insure that the flange around the mouth of the can will be maintained in a rounded condition, and that immediately after passing through this beveled opening it will be 15 projected into the grooved edge of the cap which is awaiting with the result that prior to the release of the can from the star wheel 19 and the mold member 63, the cap will be properly fitted over the can and its marginal flange will engage 20 the flange around the mouth of the can to prevent the can from again being distorted. When in this assembled condition, a can and cap may be seamed together by a suitable double seaming mechanism.

25 It will thus be seen that by the structure here disclosed, it is possible to feed a can to a double seaming machine while insuring that the cap feed mechanism will not be actuated unless a can is fed, and thereafter insuring that the cap will be 30 successively moved to marking and seaming stations, arriving at the latter station coincident with the arrival of the can which initiated the feeding of the respective cap, and it will further be seen that by the structure here disclosed caps 35 may be rapidly cut from a cap stack and fed to the marking and seaming machines at high speed and in a manner to be easily assembled with the can while means are operating to round the can and to maintain it in its rounded condition until 40 a cap has been applied thereto.

While I have shown the preferred form of my invention as now known to me, it will be understood that various changes may be made in the combination, construction and arrangement of 45 parts by those skilled in the art, without departing from the spirit of the invention as claimed.

Having thus described my invention, what I claim and desire to secure by Letters Patent is:—

- 50 1. In a double seaming machine having a seaming station and a can runway along which cans move to said station, cap stacking means associated with said seaming station, a cap carriage adapted to reciprocate beneath the stacking means, said carriage having parallel blades engaging diametrically opposite edges of the lowermost cap in the stack to remove the cap from the stack as the carriage moves to a retracted position, the carriage having means for positively engaging the cap thus removed from the stack and 55 advancing it to the seaming station on the advance movement of the carriage, said carriage normally being at rest, a driving head at one end of the carriage, means for constantly reciprocating the same in the plane of the carriage, lock 60 means by which the driving head may be disposed in operating relation to the carriage to cause the carriage to move in unison therewith and means whereby the presence of a can in the runway will permit actuation of the lock means.
- 65 70 2. In a double seaming machine having a seaming station and a runway along which cans are delivered to said station, a cap feed mechanism comprising cap stacking means, a cap carriage adapted to reciprocate beneath the stack, means forming a part of said carriage for removing the

lowermost cap from a stack of caps, means forming a part of said carriage for advancing said cap to a point intermediate the stack and the seaming station and other means forming a part of the carriage to act during the second stroke thereof to advance said cap from said intermediate position to said seaming station and a constantly operating driving means for said cap carriage normally disconnected therefrom.

3. In a double seaming machine having a seaming station and a runway along which cans are delivered to said station, a cap feed mechanism comprising cap stacking means, a cap carriage adapted to reciprocate beneath said cap stacking means, means forming a part of said carriage for removing a lowermost cap from the stack of caps, means forming a part of said carriage for advancing said cap to a point intermediate the stack and the seaming station and other means forming a part of the carriage to act upon the second stroke thereof to advance said cap from said intermediate position to said seaming station, a constantly operating driving means for said cap carriage normally disconnected therefrom, and means effected by a can passing along the can 100 runway to the seaming station whereby the driving operation of the carriage may be initiated.

4. In a double seaming machine having a seaming station at which a can and cap are assembled, a can runway along which cans may travel to said station, a cap runway leading directly to said station, means for positively feeding cans along the runway to the seaming station, cap stacking means, a marking device positioned intermediate the cap stack and the seaming station, and means 105 for first moving a cap from the cap stack to the marking device and means to move the cap from the marking device to the seaming station coincident with the delivery of a can thereto.

5. In a double seaming machine having a seaming station at which a can and a cap are assembled, a can runway along which cans may travel to said station, a cap runway, means for positively feeding cans along the runway to the seaming station, cap stacking means, a marking 110 device positioned intermediate the cap stacking means and the seaming station, means for first moving a cap from the cap stack to said marking device and subsequently moving the cap from the marking device to the seaming station coincidentally with the delivery of a can thereto, said cap moving means being normally at rest, constantly moving means by which said cap moving means may be operated, means for establishing a driving connection between said cap moving means and the constantly operating means 115 and means normally holding said cap moving means and driving means in a disconnected relation to each other except when a can passes along the runway to the seaming station.

6. In a double seaming machine having a seaming station to which cans and caps may be successively fed, a star wheel formed with a pocket adapted to embrace substantially half of the circumference of the can, a horizontally reciprocating cap feed member, a cap supporting ring at the seaming station and onto which the cap is delivered, a mold member carried therewith and cooperating with the star wheel to embrace and round a can, and means for lifting the can while 145 held by said mold member to project its mouth into the annular recess of the cap prior to the performance of the double seaming operation thereon.

7. In a cap feeding device for seaming ma- 150

chines, a constantly reciprocating driving head, reciprocable cap separating knives, a pivoted key, means operated by cans in transit to release the pivoted key, and spring pressed means to effect union between said driving head and said reciprocable cap separating knives when said key has been removed.

8. In a cap feeding device for seaming machines, cap stacking means, a constantly reciprocating driving head out of contact therewith, a reciprocable carriage, said carriage being normally in an inoperative position disconnected from any actuating mechanism, and means whereby said driving head and said carriage may be connected and reciprocated as a unit.

9. In a cap feeding device for seaming machines, cap stacking means, a constantly driven driving head out of contact therewith, a cap carriage, said carriage being normally in an inoperative position disconnected from any actuating mechanism, and means whereby said driving head and said carriage may be connected and driven as a unit.

10. In a cap feeding device for seaming machines, a cap feed mechanism comprising a cap stacking means, a constantly driven driving head out of contact therewith, a cap carriage, said car-

riage consisting of a cross-head carrying a pair of parallel feed blades to carry a cap adjacent the seaming means, and means whereby said driving head and said carriage may be connected and driven as a unit.

11. In a cap feeding device for seaming machines, a cap feed mechanism comprising a cap stacking means, a constantly reciprocating driving head out of contact therewith, a reciprocable carriage, said carriage consisting of a cross-head carrying a pair of forwardly projecting parallel feed blades, and means whereby said driving head and said carriage may be connected and reciprocated as a unit.

12. In a cap feeding device for seaming machines, a constantly reciprocating driving head, reciprocable separating knives, a reciprocable carriage, said carriage being normally in an inoperative position disconnected from any actuating mechanism, a pivoted key, means operated by cans in transit to release the pivoted key, and spring pressed means to effect union between said driving head and said reciprocable separating knives and said carriage when said key has been released.
